UNITED STATES PATENT OFFICE.

WILLIAM E. WINE, OF TOLEDO, OHIO.

HOPPER-CAR-DOOR FRAME.

REISSUED

Application filed November 6, 1926. Serial No. 146,716.

My invention relates to a hopper car door frame for application to railway cars of the hopper type, and has for its object to provide a strong and simple frame unit serving to strengthen the hopper and ensure efficient performance by the door of its duty of preventing loss of lading.

A primary feature of the invention consists in forming a hopper car door frame with door seat portions which border the sides and lower edge of the lading discharge opening thereof, the said frame being formed with sealing flanges projecting outwardly from the door seat portions in spaced relation to said opening.

A further feature of the invention consists in providing the hopper door frame with door seat portions which are embraced by outwardly projecting sealing flanges disposed at the sides and along the lower edge of the cargo discharge opening, a plurality of spaced hinge lugs being disposed on opposite sides of the said opening in alignment with the sealing flanges respectively adjacent thereto, and the said hinge lugs being integrally united to the adjacent sealing flanges outwardly of the plane of the door seat portions of the frame.

Another feature of the invention consists in forming the opposite sides of the frame with inwardly extending flanges for attachment of hopper side sheets and with brackets projecting laterally from said flanges to provide means of attachment to the car frame, the flanges being divergent upwardly and each having relatively inclined portions, and the brackets being integrally united to the flanges respectively adjacent thereto substantially at the junction of the inclined portions.

Other features of the invention relating to combinations of parts and advantageous details of construction will appear and be particularly pointed out in the claims.

In the drawings illustrating a preferred embodiment of the invention,—

Figure 1 is a side elevational view of a portion of a railway car hopper having a door frame embodying the invention applied thereto, the door being omitted.

Figure 2 is a vertical sectional view of the construction shown in Fig. 1, illustrating the relation of the door to the door frame when the door is shut.

Figure 3 is an end elevational view of the construction shown in Fig. 2, a portion of the door being broken away.

For the purpose of illustrating the inven-

tion a well known form of hopper has been shown. It comprises an inclined bottom or chute plate 1 and downwardly converging side sheets 2 bent along their lower edges to provide inwardly extending flanges which overlap the neighboring edge of the chute plate 1. The side sheets 2 are secured to the plate 1 by rivets 3 in the usual manner.

Secured to the bottom plate 1 and side plates 2 at the discharge end of the hopper, as by means of rivets 4, is a door frame 5 which is preferably made of cast steel. The cargo discharge opening 6 of this frame is preferably rectangular and centrally located. At the sides and along the lower edge of this opening are door seat portions 7 which are overlapped by the door 8 when the latter is in closed position. The door is preferably of the sheet metal type. Bordering the door seats 7 and in spaced relation to the margins of the cargo discharge opening are outwardly projecting sealing flanges 9 positioned so as to be in close proximity to corresponding outwardly projecting side flanges 10 and bottom flange 11 of the door. These flanges upon the door and frame cooperate to prevent loss of fine lading.

Above the door opening the frame is provided with a plurality of pairs of hinge lugs 12 to which the hinge members 13 of the door are secured by hinge pins 14. The outer one of each pair of hinge lugs is preferably disposed in alignment with the adjacent sealing flange 9 at the side of the cargo discharge opening, and said sealing flanges and corresponding lugs are integrally united, thereby reinforcing these lugs outwardly of the plane of the door seats 7.

The frame is preferably of substantially trapezoidal form and may advantageously be fashioned at its upper end with an outwardly projecting flange 15 serving to permit the frame to be secured at its upper end to a neighboring part of the car body. Extending inwardly from the upper edge of the door seat portion 7 which is below the discharge opening, is an attaching flange 16 to which the lower end of the chute plate 1 of the hopper is secured by the rivets 4. This flange, which forms an integral part of the frame, merges into inwardly extending upwardly divergent flanges to which the side sheets 2 of the hopper are riveted, each of said side flanges being preferably formed of relatively inclined portions 17 and 18, respectively. At the junctions of these angularly disposed portions of

the side flanges are laterally projecting integrally attached brackets 19 which, as illustrated in Fig. 3, provide means of attachment to adjacent parts of the car frame. If desired, the side flanges of the frame may be fashioned near their lower ends with suitable enlargements 20 constituting base plates for the mounting of door locking means.

A door frame embodying the invention is well reinforced against rough usage, effectively rigidifies the discharge end of the hopper, cooperates with the door to prevent loss of fine lading, and well protects the door against distortion and injury.

15 I claim:—

1. In a railway car, the combination with a hopper having side sheets and an inclined floor sheet, of an integral door frame rigidly secured to the hopper side sheets and floor sheet in a position forming an angle with the vertical, said frame having a cargo discharge opening and being formed with door seat portions bordering the sides and lower edge of said opening and with sealing flanges projecting outwardly from said seat portions in spaced relation to said opening.

2. A hopper car door frame having a cargo discharge opening, door seat portions bordering the sides and lower edge of said opening, sealing flanges projecting outwardly from said seat portions in spaced relation to said opening, and a plurality of spaced hinge lugs disposed on opposite sides of said opening in alignment with said sealing flanges respectively adjacent thereto, said hinge lugs being integrally united to the adjacent sealing

flanges outwardly of the plane of said seat portions.

3. A hopper car door frame having a cargo discharge opening, door seat portions bordering the sides and lower edge of said opening, sealing flanges projecting outwardly from said seat portions in spaced relation to said opening, and a flange adapted to overlap and be secured to a portion of the car hopper, said last named flange extending inwardly from the upper edge of said seat portion which is below the discharge opening and being integrally united to said portion.

4. A hopper car door frame having a cargo discharge opening and provided at its opposite sides with inwardly extending flanges having brackets projecting laterally therefrom, said flanges being divergent upwardly and each comprising relatively inclined portions, and said brackets being integrally united to the flanges respectively adjacent thereto substantially at the junction of said inclined positions.

5. A hopper car door frame having a cargo discharge opening, door seat portions bordering the sides and lower edge of said opening, and outwardly projecting sealing flanges spaced from said opening, in combination with a hinged door for closing said opening, the door being adapted to overlap said seat portions and having outwardly extending sealing flanges for cooperating with the said sealing flanges of the frame.

In testimony whereof I affix my signature.

WILLIAM E. WINE.
